United States Patent Office

Des. 176,763
Patented Jan. 31, 1956

176,763

ROADWAY MARKER

Horace B. Harshbarger, Corona Del Mar, Calif.

Application September 26, 1955, Serial No. 38,083

Term of patent 14 years

(Cl. D72—1)

Fig. 1 is a perspective view of a roadway marker, showing my new design.

Fig. 2 is a side elevational view thereof.

Fig. 3 is a bottom view.

I claim:

The ornamental design for a roadway marker, substantially as shown.
